(57) **CLAIM**

The ornamental design for a digital camera, as shown and described.

DESCRIPTION

FIG. 1 is a top, front and left side perspective view of a digital camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is top plan view thereof;

FIG. 7 is bottom plan view thereof;

FIG. 8 is a front elevational view of the digital camera of FIG.

1, showing the flash in an open position;

FIG. 9 is a rear elevational view of the digital camera of FIG.

1, showing the display panel in an open position;

FIG. 10 is a rear elevational view of the digital camera of FIG.

1, showing the display panel in an open position and rotated

90°; and,

FIG. 11 is an enlarged view of the camera lens housing pattern

of FIG. 6.

The portions of the digital camera in broken lines in FIGS. 1, 3, 4, 5, 6, 7, 9 and 10 are shown for illustrative purposes only and form no part of the claimed design. The directional arrow in FIGS. 9 and 10 indicates the direction of the movement of the claimed design in operation and forms no part of the claimed design.
